US00D676108S

(12) **United States Design Patent**
Kulikov et al.

(10) **Patent No.:** US D676,108 S
(45) **Date of Patent:** ** Feb. 12, 2013

(54) **WATER FILTER WITH TWO CARTRIDGES**

(75) Inventors: **Vladimir Mikhailovich Kulikov, Moscow (RU); Vladimir Alekseevich Zakharov, Moscow (RU)**

(73) Assignee: **DWT Deutsche Wassertechnologien GmbH, Frankfurt (DE)**

(**) Term: **14 Years**

(21) Appl. No.: **29/357,598**

(22) Filed: **Mar. 15, 2010**

(30) **Foreign Application Priority Data**

Sep. 15, 2009 (CN) 2009 3 0207695

(51) **LOC (9) Cl.** 23-01

(52) **U.S. Cl.** D23/209; D7/319; D7/317

(58) **Field of Classification Search** D23/207, D23/209, 212; D7/300, 312, 316-319, 397, D7/399, 400, 598, 600, 605, 691; 210/85, 210/98, 143, 232, 237, 266, 269, 282, 321.6, 210/435, 460, 323.1; 222/465.1, 105, 472; 99/295, 297, 319; 206/515

See application file for complete search history.

(57) **CLAIM**

The ornamental design for a water filter with two cartridges, as shown.

DESCRIPTION

FIG. 1 is a perspective view.

FIG. 2 is a left-hand view.

FIG. 3 is a top view.

FIG. 4 is a bottom view.

FIG. 5 is a right-hand view.

FIG. 6 is a front view; and,

FIG. 7 is a back view.
